DESIGN FOR A DRESS ENSEMBLE

Margaret Michelson, New York, N. Y.

Application February 28, 1939, Serial No. 83,247

Term of patent 3½ years

To all whom it may concern:

Be it known that I, Margaret Michelson, a citizen of the United States, residing in New York city, in the county of New York and State of New York, have invented a new, original, and ornamental Design for a Dress Ensemble, of which the following is a specification, reference being had to the accompanying drawings, forming part thereof.

Fig. 1 is the front view of a dress ensemble showing my design;

Fig. 2 is the rear view thereof.

Fig. 3 is the front view of the dress of the ensemble shown in Fig. 1 and

Fig. 4 is the rear view thereof.

The characteristic feature of my design resides in the combination on the ensemble disclosed of the specific, horizontally striped bolero jacket having diagonally striped revers and shoulder inserts, in association with the specific net dress having a gathered bust portion and a wide band of contrasting material around the skirt, said band being striped in multi-colors to match the jacket, as shown.

I claim:

The ornamental design for a dress ensemble, substantially as shown and described.

MARGARET MICHELSON.
